UNITED STATES PATENT OFFICE

RODNEY JOHN WOOD, OF DAYTON, OHIO, ASSIGNOR TO REMINGTON RAND INC., OF BUFFALO, NEW YORK, A CORPORATION OF DELAWARE

CARD INDEX FILE

Application filed October 15, 1928. Serial No. 312,521.

My invention relates to card file systems, and more particularly to the arrangement and mounting means for a series of cards affording an automatic index.

In the present construction there is contemplated a file comprising a series of oscillatory carriers upon each of which are detachably supported for relative oscillatory movement a plurality of record cards or sheets arranged in eschelon whereby the top margin of each card or sheet is visible beyond the margin of a succeeding sheet. Upon such visible portion appears a name or account number, the initials, final digits or lead characters of which being arranged at different predetermined distances from the family name or index number, whereby such initials, final digits, or lead characters pertaining to different cards form vertical parallel columns. The carriers for such groups of cards or sheets are marginally separated from each other sufficiently to expose to view the margin of the topmost card or record sheet of succeeding groups, thereby entirely obviating the necessity for guide cards or tabs. The cards are detachably engaged in a slotted ladder-like support removably mounted on each carrier unit by means of oppositely extending spaced ears or tabs engageable with such support and extending beyond the terminal limit of the slot to which the card is engaged. Each card is provided intermediate such engagement ears or tabs with a re-entrant notch or gore which permits the card to be contracted or warped sufficiently to enable the attachment ears to be introduced through the slot of the support whereupon the inherent tension of the cards will maintain such interlocked engagement.

The object of the invention is to simplify the structure as well as the means and mode of operation of card index record files whereby they will not only be cheapened in construction, but will be more efficient in operation, capable of being easily and quickly operated to find a given record, of increased visibility and unlikely to get out of repair.

A further object of the invention is to provide a construction wherein the necessity for index tabs and guide cards is minimized.

A further object of the invention is to provide a file index which will be compact enabling the placement of a large number of record cards in a comparatively small space in such manner as to be readily and quickly accessible.

A further object of the invention is to facilitate the insertion and removal of cards from the file by eliminating mechanical locks, holders, or retainers and providing a simple form of engaging means upon the card itself.

A further object of the invention is to provide a filing arrangement wherein the omission or misplacement of a card or record sheet becomes immediately noticeable and serves as an automatic indicator or check of such error.

A further object of the invention is to provide an improved form of record card or sheet having integral interlocking means for engagement with a supporting member, the sheet being arranged to facilitate the engagement and disengagement thereof with such support.

A further object of the invention is to provide an improved form of carrier units for a plurality of record cards or sheets, and to further provide for the marginal separation of such carrier units whereby the record card of each of a succession of such carrier units will be simultaneously visible.

A further object of the invention is to provide an improved form of guide indexing for the individual cards of a series.

With the above primary and other incidental objects in view, as will more fully appear in the specification, the invention consists of the features of construction, the parts and combinations thereof, and the mode of operation or their equivalents, as hereinafter described and set forth in the claims.

Referring to the accompanying drawings wherein is shown the preferred but obviously not necessarily the only form of embodiment of the invention, Fig. 1 is a perspective view of a plurality of carrier units each supporting a group of record cards and embodying the invention forming the subject matter hereof. Fig. 2 is a detail view illustrating

the manner of engagement and disengagement of a record card from the common slotted support which has been shown separated from the carrier unit. Fig. 3 is a side elevation of several carrier units and their attached record cards. Fig. 4 is a perspective view from the front of a carrier unit and a portion of the card support from which cards have been removed. Fig. 5 is an elevation of a record card removed from its support. Fig. 6 is a perspective view illustrating a numerical index system applied to the present file. Fig. 7 is a perspective view of a slide or tray type file in which the present invention is incorporated. Figs. 8 to 11 illustrate a further modification. Fig. 8 is a perspective view of a modification of the file wherein the cards are contained in a series of substantially upright trays. Fig. 9 is a perspective view of one of the trays removed from the series. Fig. 10 is a transverse sectional view of a tray such as shown in Figs. 8 and 9. Fig. 11 is a detail view illustrating the interconnection of a series of trays by hinged links into a book-like group.

Like parts are indicated by similar characters of reference throughout the several views.

It is the usual practice in the construction of card index files to employ index tabs or guide cards bearing designations A, Aa, Ab, Ac, etc. The larger such files may grow, the greater the necessity for such index tabs, and the greater will be the number of such tabs or cards required. Because of their exposure to wear and soil, such guide tabs are frequently of celluloid or provided with celluloid facings. In some instances transparent celluloid protectors are provided for the record cards. Such use of index tabs and guides not only increases materially the fire hazard, but such guides unnecessarily extend the size of the file occupying space otherwise usable for record sheets. Such use of index tabs and guide cards also materially increases the cost of maintenance of a filing system. The present system while eliminating the necessity for such index tabs or guide cards, materially reduces the space required for a given number of records and minimizes the fire hazard. It also enables the insertion of new cards easily and quickly without the necessity of shifting other cards which ordinarily involves a considerable time loss and overhead maintenance expenses. In the present instance a card may be inserted in any slot in a card support, it being immaterial whether the card is at the top, middle, or bottom of the group, it being located with equal facility in any position, whereas in the usual card index system cards must be arranged in an exact sequence.

Referring to the accompanying drawings 1-1 are a series of independent carrier units to be mounted for to-and-fro oscillatory

movement in a file drawer, cabinet or rack, as shown in dotted lines at 1' in Fig. 3. Such units 1 are preferably, though not necessarily, formed from sheet-metal. The sheet-metal panel is slotted as at 2-2 to form an intermediate tongue 3 and marginal tongues 4 of the material. The intermediate flap or tongue 3 which is of considerable width is flexed rearwardly out of the normal plane of the panel and out of the plane of the marginal tongues 4-4. The flaps or tongues 3 and 4 are held in such distended or warped relation by means of a space bar 5 interposed between the bottom margins thereof. Such space bar has been shown as an inverted channel-shaped bar, the side margins of which are upturned at 6 to embrace the lower margins respectively of the flaps or tongues 3 and 4. Formed from the material of the flaps or tongues 4 and projected rearwardly out of the plane of such portion are inwardly projecting retaining fingers or ears 7 for engagement with a slotted card support to be hereinafter described. Adjacent to their top margins the carrier units 1 are provided with rearwardly projecting spacer portions 8, which for simplicity of manufacture have been shown in the form of substantially V-shaped channels or ribs. It is obvious however that other forms of spacing projections may be employed in lieu thereof. Such spacer means, of whatever form, serves to marginally separate the carrier units 1 to expose to view therebetween the margins of the topmost card of the group carried thereby, which serves as an index or guide. Through the separation of the carrier units by the spacer means 8, the topmost card of each group throughout the file is rendered simultaneously visible. Thus it is only necessary to glance back along the top of the carrier units in order to select a desired record which may be indexed either by name or by number. Such visibility of the record cards is illustrated in Fig. 1.

Detachably engaged with each of the carrier units 1 is a card support 10 comprising a sheet of flexible material preferably tag board, but which might be metal, celluloid, fiber, or like material. This card support 10 is provided with a series of spaced transverse slots 11 which converts the sheet into a ladder-like structure. The unslotted ends of this support 10 are inserted from the front rearwardly through the vertical slots 2 of the carrier unit 1 and the terminal margins of the support 10 are interengaged beneath the retainer fingers or ears 7. This presents the intermediate slotted portions 11 of the support 10 in position overlying the middle flap 3 of the carrier unit. This card support 10 is readily detachable from the carrier unit 1 and the record cards 12 are in turn easily disengagable from the support 10.

Record cards 12 may be of any size, shape or proportions, and may bear any desired im-

printed record form. The cards 12 are each formed at their bottom margins with a short tab or offset portion 13 of less width than the card, terminating at its opposite sides in integral fingers or ears 14 for interlocking engagement with the support 10. The locking ears 14 are spaced apart a distance equivalent to the length of the slot 11 of the support 10 so that such locking ears or fingers 14 overhang the terminal limit of the slot 11 at each end thereof, as shown by dotted lines in Fig. 1. Such overlapping relation of the locking ears or fingers 14 with the terminals of the slots 11 affords a secure interlock which cannot readily become accidentally disengaged.

To facilitate the insertion or removal of the record card 12 from the support 10, the lower margin of each card is slit or notched as at 15 preferably, though not necessarily, by removal of an acutely triangular gore. The width of this notch at the margin of the card is substantially equal to the extent of one ear or finger 14 and the notch affords sufficient clearance for the retraction of one or the other of the locking ears or fingers 14 out of overlapping engagement with the support 10 at the end of the slot 11. This retraction of the engaging finger or ear 14 is effected by warping the record card 12 as shown in Fig. 2. Such adjustment is effected by bringing the margins of the notch 15 into close relation which results in a transverse constriction of the tab 13 and permits one or the other of the engagement ears or fingers 14 to be inserted into or removed from the slot 11 while the opposite ear or finger 14 is engaged in overlapping relation with the support sheet 10 at the opposite end of such slot. This operation is clearly illustrated in Fig. 2. The record cards 12 being of equal size and extent and being individually engaged in different slots 11 of the supports 10, the cards are presented in overlapping relation whereby the top margin of each succeeding card is presented to view above the margin of the preceding card. The interlocking connection of the card 12 with the support 10 affords a flexible or hinged joint enabling the oscillatory adjustment of the card forwardly and downwardly, as illustrated in Fig. 3, to expose to view the record data upon any underlying card or sheet. During such movement the marginal attachment portion 13 has a turning motion within the space intermediate the slotted support 10, and the rearwardly deflected intermediate flap 3 of the carrier unit. This rearwardly flexed portion 3 of the carrier forms a protective housing for the locking ears or fingers 14 and the supporting tabs 13, and prevents their interference with the support and cards carried by a unit in the rear. The support 10 being flexible, may yield or warp somewhat during such swinging motion, if necessary, to clear the rearwardly flexed flap 3 of the carrier by

the margin of the tab 13. Such tab portion and interengaging fingers or ears 14 being enclosed and protected by the rearwardly distended flap 3, there is little or no danger of such locking portions being torn or distorted. 70

To indicate how the omission of a record card from the group becomes at once visibly apparent, the fifth card from the bottom in Fig. 1 has been omitted. This causes a double spacing between cards and exposes upon the succeeding card matter which would ordinarily be concealed from view in the normal position of the card, and may even include a notation of "card missing". Upon the removal or omission of a card, such loss is at once apparent upon opening the file to such card group. 75

While the invention has been thus far described in connection with a file structure involving oscillatory leaves or carriers, it will be understood that it is not limited to such mounting, but the present card and their support 10 with the interlocking engagement as described may be embodied in a tray type of file wherein the cards are filed flat and where-in the series of cards in each tray or filing unit may be continued to any desired length. Such structure is illustrated in Fig. 7. In such installation the slotted support sheet 10 may be of any desired length to accommodate any number of cards. The cards are interlocked with the support sheet in the manner before described and the assembly is laid flat within the tray 16. The slotted support 10 carrying the groups of record cards 12, may be arranged in various assemblies or contained in cabinets or mountings of various types, of which there are numerous different arrangements now upon the market. Some of these holders or carriers are hinged upon vertical axis for swinging motion, book-fashion, while others are horizontally disposed. Such methods of mounting index cards or records now commonly used upon the market, form no part of the present invention per se, and hence have not been herein illustrated. The scope of the present invention, however, includes the application of the present slotted support 10 of whatever length, and the interlocked assembly of the record cards 12 therewith, into whatever type of mounting or cabinet such elements may be installed. 100

The record cards may be alphabetically or numerically indexed. In Fig. 1 there is illustrated an alphabetical index system wherein name initials are utilized for guide or lead purposes. Each record card 12 has provided at its top margin, in position to be exposed beyond the margin of an adjacent card, a space for the entry of a family name and in juxtaposition thereto, a uniform series of alphabetically designated spaces in which to enter the initials of the given name. The alphabetical designation of such spaces is 110 115 120 125 130

normally concealed beneath the adjacent card when the cards are in assembled relation. However, the initials entered in such spaces appear in vertical columns formed by the 5 registering succession of spaces on succeeding cards. Like initials appear in the same columns and unlike initials in different columns located different distances from the family name designation proportionate to the alphabetical sequence of such initial letters. While there may be in the file a large number of cards bearing the same family name, such as the name Smith, it is quite unlikely that any considerable number of these will possess 10 the same first name initial and even more unlikely that there will be any duplication of the second name initial. In locating the desired name, it is not necessary to follow through a large series of similar family 15 names such Morgan, Martin, Moran, Megan and the like, but, if one is in search of the name George I. Moses, he glances down the "G" column until he finds an intial G entered therein. Obviously there will be a much less 20 number of first name initials G than there are family names in the family group. If the searcher finds a second initial "I" associated with the G, it will be quite likely to be the name sought, which can be ascertained 25 by a glance at the family name column. In any event there will be very few duplications of first and middle name initials in a given section of family names. This very greatly facilitates the location of a given record card 30 and enables a particular card to be selected with great rapidity. Likewise if a card is misplaced in the file, and a search is made for such lost card, it can be much more quickly located by a search of the initial column 35 corresponding to the first or given name 40 initial, than by a search of the family name column. This system of alphabetical indexing by first and middle name initials, forms no part per se of the present invention, but 45 is the subject matter of a copending application Ser. No. 672,322 filed Nov. 2, 1923.

In Fig. 6 there is shown a modification of 50 such index system in which the cards are numerically identified. At the left of the cards is a column 17 for the primary index numeral, while adjacent thereto are ten 55 spaces, which, registering with those of adjacent cards, form ten columns upon the card group to receive the terminal digits one to nine and the naught in consecutively disposed relation. Like terminal or lead digits are found in the same column and unlike 60 digits are located in different columns spaced from the primary index numeral a distance proportionate to the value of such digits with the exception of the naught which is in either the left or the right-hand column. In this case having found the primary numerical group, a particular card is located by 65 its final digit by glancing down the final

column of registering spaces. In such case it is not at all necessary that the cards be consecutively arranged. By glancing down the column pertaining to the final digits of the number, a selection is confined to a comparatively few cards. 70

Instead of employing the hinged cards 12 as the primary record for cards of original entry, such cards may be employed merely as summary or data cards and the spaces behind such cards may be utilized as pockets for the deposit of record sheets. For example, in a banking institution, the monthly statement sheet or ledger sheet may be inserted loosely behind a card 12 pertaining to a particular depositor while upon such card 12 there may appear the customer's identification signature together with a record of loans made to the customer, the times that the account has been overdrawn, and such other data of general nature as might affect the customer's standing. By such arrangement the bookkeeper or bank accountant would have before him constantly for comparison with incoming checks, the customer's signature card and he could tell at a glance the general financial standing and reputation of the customer. Such record in this case would become more or less permanent whereas the daily ledger sheet or other accounting records which may be inserted loosely behind the customer's card 12, will be removed and replaced from time to time without the necessity of transferring such information data. Likewise in a mercantile establishment or in a garage, the hinged record card may form a pocket behind which are loosely inserted time slips or charge slips, statement forms or ledger sheets, while the hinged card 12 may bear a summary of the customer's account, the dates when billed, the number of times a customer's car has received attention, and any other information or data of more or less permanent or general character which would not necessarily appear upon the daily charge slip or monthly ledger account. 90 95 100 105 110 115 120 125

While each carrier 1 has been shown in the drawings as supporting a single group of cards 12, it is to be understood that the carriers 1 may be made of any desired width and may accommodate two or more groups of cards 12 located side by side. Such extension does not involve any structural change other than mere enlargement and duplication and hence is not illustrated in detail. 130

In those installations wherein the hinged cards 12 are not only utilized for entry of data or records, but also to form pockets intermediate such cards within which sales slips, data sheets, records, notes may be deposited, the collection of such matter may grow to considerable thickness. To accommodate such accumulation, the spacer bars 5 135

- and spacing beads or ribs 8 of the carrier are made of increased size, whereby the succeeding carrier units are separated greater distances. However, the preferable construction is one in which the rearward extension of the spacer bars 5 and offset beads or ribs 8 are substantially equal to each other. Thus whatever may be the capacity of the file group of cards 12 for accumulation of loose data sheets therebetween, the carrier units 1 are maintained in substantially parallel relation.
- In Figs. 8 to 11 there has been illustrated a further modification wherein the carrier comprises a pan-like unit 20 having marginal inturned walls or flanges 21. These carrier units 20 are to be arranged in parallel upright relation within a file box or drawer. Within the carrier unit 20 there is provided a slotted support 22 to receive the tabbed margin of the card 12 in the manner before described. In this installation however, the card 12 extends laterally or in a recumbent position rather than upright as heretofore described. The support card 22 is extended at one side and folded upon itself to form an overlying flap 25 partially covering the record cards and protecting them during the insertion of the carrier 20 intermediate adjacent carriers and during its removal therefrom. Such carrier unit 20 may be withdrawn from the series, as shown in Fig. 8, and for convenience rested on the top of adjacent carriers 20 while the record cards are upturned to afford access to underlying cards.
- In lieu of such loose assembly of the carriers whereby each is independently removable from the series, such series of carriers 20 may be interconnected in book fashion by intermediate hinged links 24, as shown in Fig. 11. By such arrangement, the units may be stacked one upon the other and may be opened at any desired point like a book to give access to the group or series of record cards carried by a particular unit 20. Such linked interconnection of the units will prevent any misplacement of the units or the intentional removal of such units from the series. Sufficient illustrations have been given to indicate the wide adaptability of the present file system and the interlocked group relation of removable and interchangeable record cards.
- It is furthermore quite practicable to employ the slotted support member with the series of interlaced or interlocked record cards without a carrier such as the carrier 1 or carrier 20. Such interlaced groups of cards with their connecting support may be arranged in upright position quite similar to that shown in Fig. 1 but omitting the metallic carriers 1. In large installations this will result in considerable saving of space.
- The fact that the groups of cards are of great-

est thickness at a mid-height point, the assembly being tapered or gradually reduced in thickness upwardly by the overlapping of the margins will afford sufficient intermediate spaces to render the top margin of the top-most card of each group visible above that of the preceding group even though the carrier be omitted.

While in the copending application before referred to, the index system involving an alphabetical succession of given name initial columns is disclosed upon a single sheet, the present index means differs therefrom by providing spaces for a basic index designation and individual guide or lead designations upon the margins of different sheets or cards to be simultaneously exposed to view. In the present system these spaces register to form columns one of which is appropriate for the entry of the basic index designations whether they be the family names or an index number minus its final digit. The spaces for the individual guide or lead indices registering with each other form a series of columns appropriate to the entry of the guide or lead indices at different distances from the column appropriate to the basic indices proportionate to the relative position of the guide or lead character in the series. That is to say, such guide or lead characters may be given name initials disposed in their relative alphabetical position or may be numbers disposed in their numerical sequence. In any event the like characters pertaining to different cards are simultaneously visible in the same column and unlike characters are simultaneously visible in different columns, which columns are formed by the registering spaces upon the exposed margins of different cards.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise the preferred form of several modes of putting the invention into effect, and the invention is, therefore, claimed in any of its forms or modifications within the legitimate and valid scope of the appended claims.

Having thus described my invention, I claim:

1. A record sheet carrier having a lower margin, slits in said carrier extending upwardly

from said lower margin, adjacent tongues formed by said slits being flexed out of a common plane and a spacer bar interposed between the flexed tongues whereby the bottom of the carrier is spread in a fore-and-aft direction.

2. A record sheet carrier having parallel spaced slots therein, and a support member for each carrier of sheet-material having therein a succession of parallel spaced slots for engagement of record sheets, the ends of the support being engageable through the slots of the carrier with the slotted portion of the support overlying the face of the carrier.

3. A record sheet carrier having a medially depressed portion, a support member having therein a succession of spaced parallel slots bridging the depressed portion of the carrier, in which slots the sheets are engageable.

4. A file device comprising a record sheet carrier having a depressed portion forming a rearwardly extending housing, and having flat supporting faces at opposite sides of the depression against which the record sheets rest, sheet-supporting means bridging such depression, and a series of record sheets engageable therewith having engaging portions projecting beyond the support into said depression.

5. A record sheet carrier having a transverse rearwardly projecting crimp located in spaced relation with its top margin, the lower medial portion of the carrier being rearwardly depressed to form a housing for interlocking portions of record cards to be carried thereby and having flat supporting surfaces at opposite sides of the depressed area forming bearing faces against which the record cards rest and means on said carrier for interlocking therewith a detachable support for said cards.

6. A carrier member for a card file apparatus comprising a member having a depressed medial portion, a slotted card support bridging the depressed portion of the carrier, means upon said carrier for detachably interlocking the slotted card support with said carrier, a series of cards and marginal tab portions upon the cards extending through the slots of said support into the depressed portion of the carrier.

7. A carrier member for a card file apparatus comprising a member having a depressed medial portion, a slotted card support bridging the depressed portion of the carrier, ears upon said carrier overhanging the slotted card support to detachably hold the support in engagement with the carrier, and a series of cards having interlocking engagement with the slotted support, the interlocking portions of which are housed in said depressed portion of the carrier.

8. In a file system of the character described, a carrier for record cards, a support

ing member engageable with said carrier and having therein a succession of parallel spaced slots in which the cards are engageable, a plurality of cards engaged in said slots and extending in overlapping relation wherein the marginal portions of succeeding cards are simultaneously visible beyond the margins of preceding cards, each card having thereon a space for a family name and contiguous thereto a succession of spaces for given name initials, the spaces of each card registering with those of other cards to form a succession of columns in which the initials of names upon different cards are simultaneously visible, with like initials in the same columns and different initials in different columns spaced from the family name columns different distances proportionate to the alphabetical sequence of such initials.

9. In a file system of the character described, a series of overlapping file cards having the margins of succeeding cards simultaneously exposed to view beyond the margins of preceding cards, the exposed margins of succeeding cards having thereon registering spaces appropriated to the entry of family names and contiguous thereto, a succession of spaces appropriate to the alphabetical succession of given name initials, the spaces on each card registering with those of succeeding cards to form a succession of columns in which are simultaneously visible the plurality of family names in one column and the plurality of given name initials pertaining to such group of family names arranged in different columns according to the alphabetical sequence of such given name initials with like initials in the same column and different initials in different columns spaced from the family name column in accordance with the relative position of such initials in the alphabet.

10. In a file system of the character described, a series of overlapping file cards having the margins of succeeding cards simultaneously exposed to view beyond the margins of preceding cards, the exposed margins having thereon registering spaces forming a succession of columns in which are simultaneously visible indices pertaining to the individual cards, one of said columns being appropriated to basic index designations, and the remaining columns being appropriated to a progressive series of indices spaced different distances from the basic indices in accordance with the relative positions of such indices in such succession whereby like indices will appear in the same column and different indices in different columns.

11. In a file system of the character described, a series of overlapping file cards having the margins of succeeding cards simultaneously exposed to view beyond the margins of preceding cards, the exposed margins having therein a space appropriate to a basic

- index designation and in spaced relation therewith, a space appropriate to an individual index designation of a predetermined series, the registering spaces of different 5 cards forming columns in which are simultaneously visible like individual index designations in the same column and different individual designations in different columns spaced different distances from the column 10 of basic designations proportionate to the relative position of the individual designation in a given series.
12. In a file drawer, a plurality of rectangular carriers supported on one edge therein 15 and adapted for movement relative to each other, a plurality of upwardly extending cards mounted on each carrier and arranged in overlapping offset relation thereon with one margin of each in visible relation, and 20 means adjacent the top and bottom margins of each carrier spacing each carrier from adjacent carriers, whereby said cards are loosely retained in a predetermined space between adjacent carriers.
- 25 13. In a file drawer, a series of carriers supported therein and adapted for movement relative to each other, a rearwardly projecting crimp portion formed in each carrier and extending thereacross in spaced relation with 30 its top margin, a plurality of upwardly extending record sheets mounted on each carrier in overlapping offset relation with one margin of each in visible relation, the crimp portion of each carrier impinging upon the record 35 sheets supported upon the succeeding carrier to space said carriers, whereby the margins of the uppermost record sheets in the respective carriers are visible from above said file drawer.
- 40 14. In a file drawer, a plurality of rectangular carriers supported on one edge therein and adapted for movement relative to each other, a support member removably mounted on each carrier and provided with a series 45 of spaced slots, a plurality of upwardly extending cards on each support member, said cards each having portions engaging in a slot thereof, one above the other to form an overlapping group of cards having one margin 50 of each card in visible relation, said cards being normally covered by adjacent carriers whereby movement between two adjacent carriers spaces the same to permit access to the group of cards on the carrier thus exposed.
- 55 In testimony whereof, I have hereunto set my hand this 4th day of October, A. D. 1928.

RODNEY JOHN WOOD.
